CLAIM

We claim the ornamental design for a tractor pellet grill, as shown and described.

DESCRIPTION

FIG. 1 is a front perspective view of a grill showing our new design;

FIG. 2 is a rear perspective view thereof;

FIG. 3 is a right perspective view thereof;

FIG. 4 is a left perspective view thereof;

FIG. 5 is a rear perspective view thereof; and,

FIG. 6 is a front perspective view thereof.

The broken lines in the drawings are for illustrative purposes only and form no part of the claimed design.
